UNITED STATES PATENT OFFICE.

HOWARD K. KING, OF PHILADELPHIA, PENNSYLVANIA, ASSIGNOR TO CHAMBERS BROTHERS COMPANY, A CORPORATION OF PENNSYLVANIA.

BRICK-MACHINE.

1,178,930.

Specification of Letters Patent. Patented Apr. 11, 1916.

Application filed July 30, 1915. Serial No. 42,689.

To all whom it may concern:

Be it known that I, HOWARD K. KING, a citizen of the United States, residing at Philadelphia, in the county of Philadelphia, State of Pennsylvania, have invented 5 a new and useful Brick-Machine, of which the following is a specification.

My invention relates to improvements in brick machines.

10 The object is to provide a compact and efficient mechanism for cutting a clay bar into required lengths.

The invention comprises an improved 15 housing and support for the wire reel formed by two annular channel members supported on a connecting hub or hollow shaft, a fixed shaft for supporting the hub or hollow shaft, which is adapted to reciprocate thereon, so that moving parts are removed and protected from clay particles.

20 The invention also comprises an improved friction gear for driving the reel including coöperating friction elements, and a brake, one friction element movable between the 25 brake and the other friction element, into engagement with the one and out of engagement with the other and vice versa, whereby the machine can be run at relatively high speeds and the power thrown 30 into the reel without shock to the mechanism and without impairing the efficiency of operation.

Referring to the drawings, which illustrate merely by way of example suitable 35 means for the embodiment of my invention, Figure 1 is a plan view of the cutter. Fig. 2 is a side elevation. Fig. 3 is a side elevation and partial section of the mechanism for driving and stopping the reel on an enlarged scale. Fig. 4 is a section on line 4—4 40 of Fig. 1, on an enlarged scale, with some of the parts removed. Fig. 5 is a vertical section on line 5—5 of Fig. 4.

Similar numerals refer to similar parts 45 throughout the several views.

The wire reel comprises the gear wheels 6 mounted and adapted to rotate in the housings 7, and connected by the cross bars 8, which support the cutting wires 9 as to 50 one end, the other ends being secured to the wire rings 10 rotatable about sleeve 11, which connects and supports the housings 7. Sleeve 11 is mounted on shaft 12 which 55 is rigidly secured at each end to stationary supports. Sleeve 11, and consequently the

housing structure forming the reel carriage, has a longitudinal movement on shaft 12, which movement is facilitated by suitably located friction reducing means, such for example, as rollers 13. The housing structure 60 or reel carriage comprising elements 7 and 11, is maintained against rotative movement by means of the channeled arms 14 rigidly connected with housings 7 coöperating with the rollers 13' mounted on the 65 stationary framework. The rollers 13' are also provided and oppositely disposed to prevent lateral play between sleeve 11 and shaft 12.

Driving pulley 15, connected with a suitable 70 source of power, is mounted on shaft 16 and driven at fixed speed. Shaft 16 is connected with pinion 17 coöperating with gear 18 on the shaft 21 which operates through the friction device 19 the cam 20, 75 which causes the reciprocating movement of the reel carriage. This operation it will be understood is controlled by the speed of the moving clay bar. One element of the friction device 19 is mounted on shaft 21, 80 the other element is mounted on the sleeve 22, which sleeve 22 is mounted on the shaft 21 and which operates the cam 20. The pulley of the regulating belt 23 is mounted on said sleeve 22. As all this mechanism 85 is old a more detailed description is thought to be unnecessary in this application.

The cutting reel is given a rotative movement for cutting through the bar of clay by the following mechanism: On driving shaft 90 16 is rigidly mounted the friction element 24. On shaft 16 is loosely mounted the sleeve 25. Upon the sleeve 25 are mounted the pinions 26. These pinions 26 coöperate with the gear wheels 6 of the cutting reel. 95 The pinions 26 as will be seen in Fig. 3, are given a sufficient longitudinal extension to permit of relative longitudinal movement of the gears 6. Sleeve 25 is provided with the two collars 30 and 31 between which is interposed the loosely mounted collar 32 having a trunnioned engagement with the bifurcated end of arm 33 mounted on shaft 34. On the same shaft 34 is mounted one end of lever 35 provided at its other or free end 100 with the roller 36 adapted to co-actuate with the cam 37 mounted on the sleeve shaft 22, which is the same shaft that carries cam 20 which operates the reel carriage. The actuation of roller 36 by cam 37 causes the 110

elevation of lever 35 and the consequent longitudinal movement to the right of sleeve 25, pinion 26 and of friction element 38 which is secured thereto. This causes the engagement of friction element 38 with the rotating friction element 24 and the consequent rotative actuation of sleeve 25, pinions 26 and the wire cutting reel geared therewith. The spring actuated latch 39 is adapted to 5 engage with a contact piece 40 which is adjustably connected with said arm 35, whereby the engagement between said friction elements is maintained, after the outer extension of cam 37 releases the friction roller 26, 10 and until the cutting reel has been given a sufficient rotative movement to carry the cutting wires through the bar of clay. It will be understood that the cam 37 is timed to engage roller 36, with respect to the actuation 15 of the reel carriage by the cam 20, so that the cutting movement of the reel will be started when the required length of clay bar has assumed proper position. As has already been stated, the carriage or housing 20 supporting the cutting reel is actuated by mechanism controlled by the movement of the clay bar so that the cutting reel has a longitudinal movement corresponding to the longitudinal movement of the clay bar while 25 the cutting wires are passing transversely through said bar.

Means for releasing the friction drive of the cutting reel and stopping the movement of same after the cutting operation: The 30 latch arm 39 is mounted on the shaft 41. Secured to shaft 41 are a pair of arms 42 carrying the parallel shaft 43 which shaft 43 is straddled by the bifurcated end of lever 44 which is pivotally mounted at 45 on the housing of the gear wheel 6. This member or lever 44 which is pivoted at 45 has an extension 47 beyond the pivot 45 which is shown curved for engagement with the rollers 46 mounted on the gear wheel 6. These 35 rollers are so positioned that one will engage with the extension 47 shortly after its adjacent set of cutting wires has passed through the bar, whereupon the latch member 39 is actuated to release the lever 35, upon which the sleeve 32 responding to the 40 actuation of spring 48, will carry or move sleeve 25 to move the friction element 38 out of engagement with friction element 24. At the same time friction element 38 is 45 brought into engagement with the conical surface 49 of the stationary brake member 50. Thus it will be seen that after the cutting wires have passed through the bar of clay the adjacent roller 46 will actuate the 50 latch and cause the disengagement between driving and driven friction elements, and at the same time the engagement between the driven friction element and the stationary brake, with a result that the cutting reel is 55 stopped at the required time. The opera-

tion of the cycle being repeated upon the return of the cam 37 to the position shown in Fig. 3. The advantage of the friction drive, thus controlled, for the cutting reel is that the machine can be run at relatively high speeds and the power thrown into the reel without any shock to the mechanism, and at the same time the efficiency of operation is in no sense impaired.

What I claim is:—

1. The combination of a suitably supported fixed shaft, a reel carriage or housing having a central sleeve slidably mounted on the shaft and inclosing the bearing portions, a wire reel rotatably mounted in the housing and means controlled by the movement of the clay bar for reciprocating the housing.

2. The combination of a suitably supported fixed shaft, a reel carriage or housing having a central sleeve slidably mounted on the shaft and inclosing the bearing portions, friction reducing means interposed between the shaft and the sleeve, a wire reel rotatably mounted in the housing and means controlled by the movement of the clay bar for reciprocating the housing.

3. The combination of a suitably supported fixed shaft provided with a longitudinal recess and friction reducing rollers seated therein, a reel, carriage or housing having a central sleeve slidably mounted on the shaft and inclosing the rollers, a wire reel rotatably mounted in the housing and means controlled by the movement of the clay bar for reciprocating the housing.

4. The combination of a suitably supported fixed shaft, a reel carriage or housing having a central sleeve slidably mounted on the shaft and inclosing the bearing portions, said sleeve provided with rollers for engaging the opposite sides of the shaft to prevent lateral play between the sleeve and shaft, a wire reel rotatably mounted in the housing and means controlled by the movement of the clay bar for reciprocating the housing.

5. The combination of a suitably supported fixed shaft, a reel carriage or housing having a central sleeve slidably mounted on the shaft and inclosing the bearing portions, means for maintaining the housing against rotative movement, a wire reel rotatably mounted in the housing and means controlled by the movement of the clay bar for reciprocating the housing.

6. The combination of a suitably supported fixed shaft, a reel carriage or housing having a central sleeve slidably mounted on the shaft and inclosing the bearing portions, means for maintaining the housing against rotative movement comprising a channel element and a coöperating roller element, one secured to the housing and the other to the stationary framework, a wire

reel rotatably mounted in the housing, and means controlled by the movement of the clay bar for reciprocating the housing.

7. The combination of a suitably supported fixed shaft, a carriage comprising wheel housings and a connecting sleeve mounted on the shaft, a wire reel comprising wheels mounted in the housings and connecting cross bars, a plurality of platen elements mounted on the sleeve, wire rings rotatably mounted on the sleeve between the platen elements, cutting wires supported between the wire rings and the cross bars and means controlled by the movement of the clay bar for causing the reciprocation of the housing.

8. The combination of a suitably supported fixed shaft, a carriage comprising wheel housings and a connecting sleeve mounted on the shaft, a wire reel comprising wheels mounted in the housings and connecting cross bars, a plurality of platen elements mounted on the sleeve, wire rings rotatably mounted on the sleeve between the platen elements, cutting wires supported between the wire rings and the cross bars, means controlled by the movement of the clay bar for causing the reciprocation of the housing and means for causing the rotative movement of the reel.

9. The combination of a wire reel and means for controlling its rotative movement comprising coöperating friction elements, one in operative relationship with the reel and the other connected with a source of power, means for moving one element into operative relationship with the other, controlled by the movement of the clay bar, means for maintaining said elements in operative relationship comprising a latch and a release therefor operated by the reel after its cutting movement.

10. The combination of a wire reel and means for controlling its rotative movement, comprising coöperative friction elements, one in operative relationship with the reel and the other connected with a source of power, means for moving one element into operative relationship with the other, controlled by the movement of the clay bar, means for maintaining said elements in operative relationship comprising a latch, a release therefor operated by the reel, after its cutting movement and a brake for stopping the movement of the wire reel, becoming effective upon the release of the friction elements.

11. The combination of a wire reel, a supporting housing therefor, said housing provided with a central sleeve having a reciprocating movement on an inclosed axial support, and means for causing said reciprocating movement controlled by the movement of the clay bar.

12. The combination of a wire reel, a sup-

porting housing therefor, said housing provided with a central sleeve having a reciprocating movement on an inclosed axial support, and means for causing the rotative movement of the reel, controlled by the movement of the clay bar.

13. The combination of a wire reel, a supporting housing therefor, said housing having a reciprocating movement on an axial support, means for causing said reciprocating movement, comprising a cam and actuating means therefor, controlled by the movement of the clay bar.

14. The combination of a wire reel, a supporting housing therefor, said housing having a reciprocating movement on an axial support, means for causing said reciprocating movement controlled by the movement of the clay bar, means for causing the rotative movement of the wire reel comprising a constantly driven friction element and a laterally moving coöperating friction element in operative relationship with the reel, means for moving said friction element into engagement with the other friction element, comprising a cam and actuating means therefor controlled by the movement of the clay bar, means for maintaining said elements in operative relationship, comprising a latch, and means connected with the reel for releasing the latch after a cutting movement.

15. The combination of a wire reel, a supporting housing therefor, said housing having a reciprocating movement on an axial support, means for causing said reciprocating movement controlled by the movement of the clay bar, means for causing the rotative movement of the wire reel comprising a constantly driven friction element and a laterally moving coöperating friction element in operative relationship with the reel, means for moving the said friction element into engagement with the other friction element, comprising a cam and actuating means therefor controlled by the movement of the clay bar, means for maintaining said elements in operative relationship comprising a latch, means connected with the reel for releasing the latch after a cutting movement, and means for separating the friction elements upon the release of the latch.

16. The combination of a wire reel, a supporting housing therefor, said housing having a reciprocating movement on an axial support, means for causing said reciprocating movement, controlled by the movement of the clay bar, means for causing the rotative movement of the wire reel comprising a constantly driven friction element and a laterally movable coöperating friction element in operative relationship with the reel, means for moving said friction element into engagement with the other friction element, comprising a cam and actuating means therefor controlled by the movement of the

clay bar, means for maintaining said elements in operative relationship comprising a latch, means connected with the reel for releasing the latch after a cutting movement, means for separating the friction elements upon the release of the latch, and braking means for stopping the rotative movement of the reel, adapted to become effective immediately upon the separation of the coöperating friction elements.

17. Operating means for rotating cutting wire reels comprising a constantly driven friction element and a coöperative friction element, a pinion connected thereto and 15 geared with the wire reel, said pinion being mounted so as to have rotative and also longitudinal movement, means for causing longitudinal movement thereof to bring the friction element connected therewith into 20 contact with the constantly driven friction

element, comprising a shifting lever and an operating cam therefor, means for returning said friction element into inoperative position, means for latching the friction element against said return, and a trip connected with said latching means adapted to be actuated by the reel after it has made a cutting movement.

18. The combination of a fixed shaft, a reel housing comprising two annular channel elements connected by a sleeve slidably mounted on the fixed shaft, a wire reel comprising annular gear wheels rotatably supported in the housing, and means controlled by the movement of the clay bar for reciprocating the housing.

HOWARD K. KING.
